United States Patent Office

Des. 186,678

Patented Nov. 17, 1959

186,678

CLOCK

Gordon Florian, Bridgeport, Conn., assignor to Sunbeam Corporation, Chicago, Ill., a corporation of Illinois

Application July 6, 1959, Serial No. 56,675

Term of patent 14 years

(Cl. D42—7)

Fig. 1 is a front elevational view of a clock embodying my new design;

Fig. 2 is a top plan view thereof;

Fig. 3 is a side elevational view; and

Fig. 4 is a sectional view taken along line 4—4 of Fig. 1.

I claim:

The ornamental design for a clock, as shown.
